WITNESSES.

UNITED STATES PATENT OFFICE.

CHARLES H. BEELER, JR., OF PHILADELPHIA, PENNSYLVANIA, ASSIGNOR
TO MACKELLAR, SMITHS & JORDAN, OF SAME PLACE.

DESIGN FOR TYPE.

SPECIFICATION forming part of Design No. 15,108, dated July 1, 1884.

Application filed May 16, 1884. Term of patent 7 years.

To all whom it may concern:

Be it known that I, CHARLES H. BEELER, Jr., (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an unshaded letter. In the A the right-hand limb of the letter is longer than the left-hand portion, and is extended below the line. The cross-line of the letter consists of the inclined line extended beyond the right-hand limb. The F, P, T, and Y are extended below the line. The left-hand portion of the H is ex-

tended below the line, its right-hand portion as well as the J, L, U, V, and W above the line. The lower portions of the K and R extend below the line. The left-hand portions of the M and N extend below the line. The up and down portions of the T and B are crossed about centrally by the short inclined line, as shown. The central lines of the W are ornamented by the short inclined lines forming, as it were, a continuation of them.

Having now described my invention, I claim as new—

The design for a font of printing-type, as shown and described.

C. H. BEELER, JR.

In presence of—
C. F. HUCH,
HERMAN METIUS.
